UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRICAL FLUSH RECEPTACLE.

Application filed October 7, 1922. Serial No. 593,001.

To all whom it may concern:

Be it known that I, ARVID H. NERO, a citizen of the United States of America, residing at New Britain, in the county of Hartford and State of Connecticut, have invented certain new and useful Improvements in Electrical Flush Receptacles, of which the following is a specification.

My invention relates to electrical flush receptacles, and particularly to flush receptacles of the screw plug type. The object of my invention is to simplify, lighten, and to reduce the number of parts and the cost of manufacture of a receptacle of this type.

15 In the accompanying drawings—

Fig. 1 is a plan view of a receptacle in which my invention is embodied;

Fig. 2 is an inverted plan thereof;

Fig. 3 is a section on the line 3—3,

20 Fig. 1;

Figs. 4 and 5 are perspective views of the two wire terminal straps of the receptacle; and

Fig. 6 is a perspective of a modification.

25 The present receptacle comprises an insulating body 6 of porcelain, or other moldable insulating material, the central area of which is substantially cylindrical and is recessed from the face of the receptacle to afford a well for the reception of the usual screw shell contact 7. From the opposite side of the central area, and on the same diameter, extend end ribs 8 and 9 of materially less depth than the body of the receptacle, 30 but of sufficient size to afford a substantial mechanical support for the metal ear pieces 10 and 11 by which the receptacle is mounted in usual fashion in an outlet box. The ribs 8 and 9 are pierced to receive the ear holding bolts 12, while the ear pieces 10 and 11 are pierced at 13, adjacent their free ends, to accommodate the screw bolts (not shown) by which the receptacle is clamped in the outlet box.

45 Projecting from the lower portion of the body 6 and adjacent, but on opposite sides of the respective end ribs 8 and 9, to which they are united, are depressed ledges 14 and 15 for the support of the wire terminal straps 16 and 17 respectively. The level of the ledges 14 and 15 is considerably above the bottom of the well 18 in which the receptacle contacts are seated. The terminal straps 16 and 17 have therefore downwardly angled reaches 19 and 20 respectively con-

nected their binding screw ends with their contact ends 21 and 22 respectively, by which electrical connection is established with the receptacle contacts. Thus, the end 21 of the strap 16 is forked to straddle the horse-shoe shaped boss 23 which projects upward from the bottom of the well 18, and to overlie the base flange 24 of the screw shell 7. The ends of the fork are tapped at 25 to receive holding screws 26 which pass through the bottom of the well 18 and mechanically secure the strap in position as well as establishing electrical contact between it and the screw shell. The inner end 22 of the strap 17 is tapped at 27 to receive the holding screw 28, which also passes through the bottom of the well and serves to mechanically and electrically connect the base of the center contact 29 over which the end 22 of strap 17 lies. Both of the latter are confined by the sides of the horse-shoe boss 23 and are thus prevented from swiveling.

50 It will be noted that there are but three holding screws, 26 and 28, piercing the body of the receptacle, and that these screws serve to mechanically secure in position both the screw shell and center contact of the receptacle as well as their associated wire terminal straps 16 and 17. The latter are supported at their free outer ends on the ledges 14 and 15, which are of sufficient mechanical strength to withstand the thrusts imposed by the turning down of the binding screws 30 to clamp the leading-in wires. The ledges are recessed at 31 to afford play for the projecting inner ends of the binding screws

55 It may be pointed out furthermore that inasmuch as the wire terminal straps 16 and 17 are directly engaged with the receptacle contacts 7 and 29, the screws 26 and 28 which establish this connection need not be of brass or other relatively expensive conductor, but may be of relatively cheap ferrous material.

60 The passageways 32 through which the wire terminal straps emerge from the center contact well 18, may be formed, during molding, by die projections passing through the bottom of the receptacle, and the necessity for using laterally movable plunger members in the forming dies is thus eliminated, while the material required to form the body of the receptacle is reduced without weakening the latter to an undesirable extent. While neither the ledges 14 and 15, 65

nor the ribs 8 and 9 extend the full depth of the receptacle, they are of sufficient ruggedness to withstand the mechanical strains imposed thereon, and are not only integral with the body of the receptacle, but also united in pairs by tie webs so that the one member of each pair reinforces the other against lateral shocks.

The construction shown materially reduces the amount of insulating material necessary for the body of the fitting, eliminates various metal members now commonly employed in receptacles of this character, makes possible an economy in the number and metal of the holding screws used to secure the conductors together and at the same time provides a rugged receptacle embodying all necessary elements and with the best possible electrical connection between the wire terminals and the receptacle contacts.

In Fig. 6 a still more economical form of center contact construction is shown, in which the contact proper 30 is integral with the wire terminal strap 31.

Other modifications will readily occur to those skilled in the art, without departing from what I claim as my invention.

I claim—

- 30 1. An electrical flush receptacle of the screw shell type, comprising a molded insulating body of generally cylindrical central shape, ribs integral therewith and projecting on the same diameter from opposite sides of the upper portion of said central body member, supporting means secured to said ribs, imperforate depressed ledges projecting from the lower portion of said central area adjacent said ribs, but on opposite sides of the latter at opposite ends of the receptacle, said ledges being connected to said ribs and shaped for the reception of binding terminals, said cylindrical central body area of the receptacle being recessed from the face of the latter to afford a depressed well having the bottom at a level below the level of the depressed wire terminal ledges and having a center contact-locating projection up-standing from the bottom of said well and extending toward one

of said depressed ledges, the wall of said cylindrical body portion being apertured in register with the depressed ledges by recesses extending through the base of the receptacle.

55

2. The combination with the construction specified in claim 1, of a screw shell contact having a base flange resting in said well and straddling said center contact-locating projection, a wire terminal strap having an offset binding screw end resting freely on one of said depressed ledges, and a bearing end to overlie the base flange of the screw shell contact, together with a second offset wire terminal strap resting at one end on the other depressed ledge and having a base portion extending downward therefrom toward the bottom of the screw shell well and entering the center contact-locating projection in said well, and a center contact associated with said second wire terminal strap, said terminal straps passing from their respective supporting ledges into the well through the apertures in the wall of the cylindrical body portion of the receptacle.

75

3. The combination with the construction specified in claim 1, of a screw shell contact having a base flange resting in said well and straddling said center contact-locating projection, a wire terminal strap having an offset binding screw end resting freely on one of said depressed ledges, and a bearing end to overlie the base flange of the screw shell contact, a second offset wire terminal strap resting at one end on the other depressed ledge and having a base portion extending downward therefrom toward the bottom of the screw shell well and engaging the center contact-locating projection in said well, together with holding screws passing through the bottom of said well, said screws engaging the ends of the wire terminal straps which project into the well and serving to mechanically secure and electrically connect the conducting members of the receptacle, substantially as described.
